UNITED STATES PATENT OFFICE.

GUSTAVE A. TANK, OF SAN FRANCISCO, CALIFORNIA.

LAMP-SHADE PROTECTOR.

SPECIFICATION forming part of Letters Patent No. 400,372, dated March 26, 1889.

Application filed April 6, 1888. Serial No. 269,892. (No model.)

To all whom it may concern:

Be it known that I, GUSTAVE A. TANK, of the city and county of San Francisco, State of California, have invented an Improvement in 5 Lamp-Shade Protectors; and I hereby declare the following to be a full, clear, and exact description of the same.

My invention relates to that class of protectors for lamp and gas shades and globes in 10 which a shield of some indestructible but translucent material—such as mica—is interposed between the shade or globe and the lamp or gas flame; and my invention consists in the constructions and combinations of devices which I shall hereinafter fully describe and claim.

The object of my invention is to provide simple and practical means for applying the protector.

20 Referring to the accompanying drawings for a more complete explanation of my invention, Figure 1 is a perspective view showing my protector in position. Fig. 2 is a vertical section.

25 A is a gas or lamp fixture having the burners *a*.

B is the shade or globe, which is supported from the fixture in the usual manner by means of a top ring, C, encircling the flanged 30 top of the shade, and set by screws *c*. The ring C is supported by radial arms D, which unite in a ring-hub, *d*, fitted upon the top or stem of the fixtures A and secured by a nut, *a'*.

E is the protector, consisting of a ring of 35 transparent or translucent material, such as mica, which, while indestructible, does not obstruct the passage of the light. This ring of mica may be made either integral or in sections, as may be found most practicable. The 40 top of the protector is secured to a metal ring, F, which has made in its upper portion the L-shaped slots *f*.

To apply the protector, it is passed up inside of the shade until its supporting-ring F 45 projects through and above the top of the shade. The leg portions of the L-shaped slots *f* pass up by the radial arms D of the shade-

supporting ring C, and when fully up the protector is turned axially, so as to pass the horizontal base portions of the L-shaped slots 50 along the radial arms D. Then the protector

is relieved and the small end portions of the slots *f* drop down over the arms, thus securing the protector in place between the shade and flame. In this position it saves the shade 55 from undue heat or sudden variations of temperature, and thus prevents breakage. The projection of the metal ring F into and through the top of the shade affords protection to the upper portion of said shade without interfering with the light.

I am aware that a protector of mica is not broadly new in this connection, and I do not claim such; but

What I do claim as new, and desire to secure by Letters Patent, is—

1. In combination with the shade or globe, the protector E, of translucent or transparent material—such as mica—and the metal ring F, to which the protector is secured by its top, 70 said ring passing up into and through the top of the shade, substantially as herein described.

2. In combination with the shade or globe and its supporting-ring with arms, the protector E, of translucent or transparent material—such as mica—the metal ring F, secured to the top of the protector, and a connection 75 between the arms of the shade-supporting ring and the metal ring of the protector, substantially as herein described.

3. In combination with the shade or globe and its supporting-ring with arms, the protector E, of translucent or transparent material—such as mica—and the metal ring F, secured to the top of the protector and having 85 the L-shaped slots *f*, whereby it may be suspended from the arms of the shade-holding ring, substantially as herein described.

4. The protector for lamp and gas shades or globes, consisting of a ring of mica having a 90 metal ring secured to its top, in which said metal ring are made L-shaped slots, whereby the protector may be suspended from the shade or globe holding frame, substantially as herein described.

In witness whereof I have hereunto set my hand.

GUSTAVE A. TANK.
